UNITED STATES PATENT OFFICE.

BENJAMIN F. WOODING, OF DENVER, COLORADO.

AUTOMATIC TRAIN CONTROL FOR CAB-SIGNALS.

1,115,364.

Specification of Letters Patent.

Patented Oct. 27, 1914.

Application filed July 15, 1912. Serial No. 709,327.

To all whom it may concern:

Be it known that I, BENJAMIN F. WOODING, a citizen of the United States, residing in the city and county of Denver and State of Colorado, have invented certain new and useful Improvements in Automatic Train Control for Cab-Signals; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means carried by the train for automatically controlling the cab signals of railway signaling systems. From the foregoing it will be understood that this invention is employed in connection with that class of railway signaling systems in which the signals are displayed or produced upon the train,—namely in the cab of the engine.

In my present improvement there is a normally closed train circuit, an electromagnet being located in said circuit and consequently normally energized, whereby its armature seats a valve and prevents the escape of air from the train pipe of the air-brake system. When, however, this circuit is broken by virtue of the existence of a dangerous condition, as the dangerous proximity of one train to another, the breaking of a rail, or other condition of similar character, the deenergizing of the train magnet releases the air valve, permitting the escape of the air, which serves to operate a warning whistle and at the same time applies the air brakes and stops the train without any action whatever on the part of the engineer or others in control of the train.

Furthermore, my present invention is employed in connection with track apparatus including track contacts which are arranged at suitable intervals and adapted to be engaged by a depending device carried by the train whereby the track circuit is intermittently closed through an electrical source carried by the train, or an external source, as may be desired. By virtue of this construction and arrangement, every time the train device engages a track contact a bell or other suitable signal in the cab is operated. The operation of this signal indicates absence of danger, and under these

conditions the circuit is constantly closed through the air-valve controlling electromagnet on the train. When, however, the track portion of the circuit is interrupted by the existence of any dangerous condition, the magnet is deenergized and the air-valve released, as heretofore stated.

The distinguishing feature of my present construction consists of an oscillatory depending device carried by the train, through which the train magnet circuit is constantly closed except when a dangerous track condition exists, whereby the said circuit is interrupted. Normally, or when the train device is not in engagement with a track contact, the magnet circuit is completed through the train device alone, while, when the train device is in engagement with the track contact, the magnet circuit is completed through the track portion of the circuit, thus maintaining the air-valve closed, at all times except in the presence of danger.

Having briefly outlined my improved construction, I will proceed to describe the same in detail, reference being made to the accompanying drawing, in which is illustrated an embodiment thereof.

In this drawing: Figure 1 is a cross section taken through the cab of a locomotive, illustrating the mechanism employed in connection with my present invention. Fig. 2 is a longitudinal section taken through the electromagnet carried by the train, and the warning whistle, the magnet being shown in connection with a pipe in communication with the automatic air of the brake system, the parts being shown on a larger scale. Fig. 3 is a similar view showing the magnet deenergized and the air-valve released. Fig. 4 is a view of the train device shown on a much larger scale than in Fig. 1. Fig. 5 is a view of the same construction viewed at right angles to Fig. 4, Fig. 5 being a view looking in the direction of arrow 5, Fig. 4.

The same reference characters indicate the same parts in all the views.

Let the numeral 5 designate the cab of a locomotive provided with wheels 6, connected by an axle 7, the wheels engaging the track rails 8 and 9.

Mounted in the cab of the locomotive, or any suitable part of the train, is a source of electricity, as a battery 10, the same being connected with an electromagnet 12, provided with an armature 13, the armature carrying a valve piece 14 which closes an air

pipe 15 when the magnet is energized. The magnet is also equipped with a warning whistle 4, which is sounded by the escaping air when the valve 14 is open. The coil of 5 the magnet is so arranged that the passage of the current through either of two distinct circuits energizes the magnet and maintains the air valve in the closed position.

A U-shaped train device 16 is trunnioned, as shown at 17, on each of two journal boxes 18 mounted on opposite sides of a locomotive. The trunnions 17 of this train device are mounted in side plates 19 applied to the opposite sides of a journal 15 box, but insulated therefrom as shown at 20. By virtue of this construction the U-shaped frame device 16 is normally insulated from the train. This U-shaped device is composed of parallel arms 21 which 25 occupy positions on opposite sides of the journal box, the said arms being connected at their lower extremities by a transverse member 22. One of the arms 21 of the train device is equipped with an upwardly 30 extending contact member 23 which normally engages a contact clip 24 which is mounted on an angle bracket 25, but insulated therefrom by insulating members 26 and 27. Connected with the contact clip 35 24 is a bolt 28 with which is connected one extremity of a conductor 29 which includes the arm F of a double pole switch D, the said conductor being electrically connected through wire 47 with a terminal 30 of the coil of the magnet 12. From one pole 31 of the battery 10 a wire 32 leads to the opposite terminal 33 of the coil. From the same pole 31 of the battery, electrical communication is established through a part of 40 the coil, with a terminal 3, a wire 34 leading from the last named terminal to a bell 35, or other signal carried by the train. From the bell also leads a conductor 36 to the metal body of the locomotive whereby 45 the current may pass through a wheel 6 to a rail 9 and thence through a wire of the track circuit of any block, the current returning through a wire 38 to a member 39 of a track contact 43, which also includes a yielding member 40 pivoted at 41 and normally pulled toward a member 39 by a spring 42. When a train reaches one 50 of these track contacts, which is designated in its entirety by the numeral 43, the U-shaped train device, or blade, passes between the two members 39 and 40, thus completing the track circuit. In this event the train device 16 is actuated to disengage the contact member 23 from the contact 55 clip 24 whereby the magnet circuit is broken at this point but established through the track circuit, the magnet circuit in both cases remaining intact in the absence of danger, since the return current through 60 the conductor 38 of the track circuit may

be understood to pass from the track contact 43 into the train device 16 which includes a switch arm G, the last named conductor communicating through the switch arm 45 with the opposite pole 46 of the battery 10. From this it will be understood that the track contacts 43 are located 70 in such proximity to each other that the track circuit is tested, so to speak, at comparatively short intervals. Normally, and 75 in the absence of danger, whenever the train device 16 engages a track contact 43, the bell 35 will be sounded during such engagement, thus notifying the engineer that the track is clear, and also that the signaling apparatus is in perfect condition. But if, when the train device engages a track contact 43, any element of the track circuit is disrupted so as to break such circuit; or, if there is a train in dangerous 80 proximity whereby the current in the track circuit is short-circuited whereby the magnet 12 is deenergized, the air pressure in the pipe 15 will immediately lift the armature 13 of the magnet, opening the valve 90 14 and permitting the escape of the air, whereby the whistle is sounded, and the brakes simultaneously applied.

From the foregoing description the operation of my present invention will be 95 readily understood. Assuming that the train device 16 is free from a track contact 43, or in the position shown in full lines in Figs. 4 and 5, the circuit, through the magnet 12, may be traced as follows: 100 From the pole 31 of the battery 10 through the conductor 32 to the terminal 33 of the magnet coil, and thence from the opposite terminal 30 through a conductor 47 and thence through either conductor 29 and its 105 arm F to the double pole switch D, to the bolt 28, thence to the clip contact 24, thence through the contact member 23 carried by the train device 16, thence through the latter to the plate 19 on the opposite side of 110 the journal box and thence through one of the conductors 44 and the switch arm G of the double pole switch D, and through the switch arm 45 to the opposite pole 46 of the battery, completing the circuit 115 through the entire coil of the magnet 12 whereby the armature 13 is held in the position shown in Fig. 2 and the air-valve 14 closed. Assuming, however, that one of the train devices 16 is in engagement with 120 one of the track contacts 43, as the one at the left in Fig. 1, in which event the switch arm 45 is in full line position in Fig. 1, the path of the circuit may be traced as follows: From the pole 31 to the battery 125 10 through the conductor 32 through the terminal 33 of the magnet and thence through a part of the coil to the intermediate terminal 3 of said coil and thence through the conductor 34 to the bell 35, 130

thence from the bell through a conductor 36 to the metal body of the locomotive, whence the current passes through a wheel 6 and track rail 8 to a line conductor 37, thence through a line circuit and back through the conductor 38 of such circuit to the contact 43, thence from said conductor through the train device 16 to the plate 19 at the left of Fig. 5 and thence through the conductor 44 and its double pole switch arm G, and the switch arm 45 to the opposite pole 46 of the battery circuit.

The U-shaped device 16 is normally spring-held in position to cause its contact member 23 connected with one arm to engage the stationary contact clip 24. This is accomplished by means of leaf springs 48 which are mounted on a stationary part of the train, as shown at 49. The movement of the device 16, under the influence of the springs 48, is limited by adjusting the screws 50 which are threaded in stationary brackets 51 and engage the arms 21 of the device 16 on the opposite side from the springs 48.

With reference to the coils of the magnet 12 it should be stated that the current of the internal circuit passes through the entire coil of the magnet, entering at the terminal 33 and passing out at the terminal 30, while when the current passes through the external circuit, it is intended that the current should only pass through approximately half of the magnet coil, and it may be assumed that the terminal 3 is located about midway of the length of the coil, thus diminishing the resistance of the magnet coil to the passage of the current, where the latter must trace the external circuit.

The description heretofore given relates specifically to a construction in which the electrical source 10 carried by the train is employed for both the internal and external circuits. It is often advisable, however, to employ the train battery for internal circuit only, and an external source of electricity where the current must trace the track circuit and for this reason the double pole switches D are employed. It should be understood that if the battery carried by the train were to be used as the only source of electricity for both the internal and external circuits, no switches would not be needed. Then, however, it is desired to use the train battery for the internal circuit and a distinct electrical source arranged along the track, when the train device is in engagement with the track contact 43, the double pole switch is shifted from the full line position (see Fig. 1) to the dotted line position, and in this event it will be seen that the internal circuit will be completed through the battery 10 the same as before,—that is to say, when the arm 23 is in engagement with the contact clip 24. The path of the current,

however, will be slightly changed, since after leaving the double pole switch arm F, the current will pass through a short conductor H to a point J and thence through a part of the conductor 44 to one arm of the U-shaped train device, and thence through the said device and the arm 23 of the contact 24, thence through a portion of the conductor 29 to the switch arm G of the double pole switch D and thence through the other part of the conductor 44 to the switch arm 45 and thence to one pole of the battery. However, when the train device 16 is in engagement with the track contact 43, the battery 10, carried by the train, will be cut out of the circuit and a track battery, or other electrical source A, employed. In this event the conductors 37 and 38 are in connection with the opposite poles B and C respectively of the battery A. In this event the current may be said to pass from the pole C of the battery A through the conductor 38 to the track contact 43, thence through the train device 16 and the plate 19 at the left in Fig. 5 through a portion of the conductor 44, thence through the short conductor H to the switch arm F of the double pole switch D, thence through a portion of the conductor 29 and the conductor 47 to the terminal 30 of the magnet 12, thence through the coil to the terminal 3 and thence from said terminal through the conductor 34 to the bell, thence from the bell to the conductor 36 to a metal part of a locomotive, thence through a wheel 6 and the conductor 37 to the opposite pole B of the external source of electricity, completing the circuit.

A part of the external circuit together with the source of electricity A is indicated by dotted lines, to harmonize with the dotted line positions of the double pole switches D carried by the train, since when the double pole switches are in the dotted line position the train battery is cut out when the train device is in engagement with the contact 43 and the circuit is supplied with current from the external source A. It must be understood, however, that when the train device 16 is not in engagement with the track contact 43, the internal circuit is completed through the train source 10, while the double pole switches are in the dotted line position, the current, however, passing through the U-shaped train device in the opposite direction from that which it takes when the double pole switches are in the full line position.

Attention is called to the fact that the contact clip 24 is relatively long, whereby the electrical connection between the arm 23 and the said contact is prolonged after the train device 16 begins to move from its normal position to the dotted line position in Fig. 4. The object of this prolongation of the contact relation between the parts 23

and 24 is to maintain the circuit intact through the electromagnet 12 until the train device 16 shall have reached such position with reference to the track contact 43 that 5 the circuit is closed through the last named contact before it is broken through the contact clip 24, which is closed at the top to prevent the entrance of rain, snow, and other foreign matter or substances.

10 Having thus described my invention, what I claim is:

1. Railway signaling apparatus including a source of current carried by the train, signal devices also carried by the train and 15 supplied by the said source, a rigid U-shaped device whose arms are pivotally connected with the opposite sides of an axle journal box of the train, one arm of which is constantly electrically connected with one pole 20 of said source and the other arm normally electrically connected with the other pole, the device being mounted to oscillate whereby its connection with the last named pole is broken.

25 2. In railway signaling apparatus, the combination with a train circuit, of a rigid U-shaped device whose arms are pivotally connected with the opposite sides of an axle journal box of the train, one arm of said 30 device being constantly in electrical communication with one pole of said circuit, while the other pole is arranged to be intermittently engaged by the other arm of said device.

35 3. Railway signaling apparatus including a train circuit and a U-shaped device, the arms of the latter being pivotally connected with the opposite sides of an axle journal box of the train, one of said arms being constantly in electrical communication with one 40 pole of said circuit, the said device being held normally in such position that the other

arm is in communication with the other pole, the said device being movable whereby said last-named connection is broken.

4. Railway signaling apparatus including a train circuit, a U-shaped device whose arms are pivotally connected with the opposite sides of an axle journal box of the train, a stationary contact also carried by the 50 train, a contact member connected with one arm of said U-shaped device, the U-shaped device being spring held to hold said contact member in engagement with said stationary contact, a circuit with one pole of which the 55 stationary contact is electrically connected, the opposite arm of the U-shaped device being constantly in electrical communication with the other pole of the circuit, the U-shaped device being movable to disengage 60 its contact member from the said stationary contact for the purpose set forth.

5. Railway signaling apparatus including a U-shaped device carried by the train and pivotally mounted on opposite sides of an 65 axle journal box, springs acting on said U-shaped device to hold it in a predetermined position, adjustable means for limiting the movement of the U-shaped device in response to said spring, one arm of the 70 U-shaped device being equipped with a contact member and a circuit carried by the train with one pole of which the said contact member is normally in electrical communication, while the opposite arm of the 75 U-shaped device is constantly in communication with the other pole.

In testimony whereof I affix my signature in presence of two witnesses.

BENJAMIN F. WOODING.
